SHIPPING CONTAINER

Mason Foshee, Jacksonville, Fla.

Application June 6, 1934, Serial No. 729,325

9 Claims. (Cl. 217—12)

This invention relates to shipping containers and more particularly to wire or band bound shipping crates characterized by the several sections forming the body portion thereof being 5 flexibly yet permanently secured to each other whereby to form a collapsible enclosing structure requiring only the operation of opening out prior to assembly therewith of the heads, or top and bottom, as the case may be.

10 Among the objects of the present invention may be noted the provision of a knock-down or collapsible crate of improved design; the provision of a crate of the above character so constructed that either a flush or "bulge" type of top or cover may be utilized therewith; the provision of a crate which may be fabricated inexpensively and in quantity by machine methods; the provision of a crate which is light in weight and constructed from light, thin materials but 15 which is so reinforced as to provide a structure possessing a high order of strength, durability and rigidity; the provision of a knock-down or collapsible crate which, when collapsed, takes up a minimum amount of space, which may be shipped flat, and which requires the minimum amount of manipulation to assemble the same 20 while at the same time requiring no expensive equipment in assembly.

Other objects will be in part obvious and in 30 part hereinafter pointed out in connection with the accompanying sheet of drawings illustrating an embodiment of my invention.

In the drawings—

Fig. 1 is a perspective view of an assembled 35 crate in accordance with the present invention, the cover or top being shown in an intermediate stage of association therewith;

Fig. 2 is a view of the collapsed body portion of the crate illustrated in Fig. 1;

40 Figs. 3, 4, 5 and 6 are transverse vertical sections through a crate showing the various steps of assembly;

Fig. 7 is a view showing a modified form of 45 crate structure; and

Fig. 8 is a detail of a modified crate cover or top.

Referring to the drawings, of which Figs. 1-6 are illustrative of one form of crate in accordance with the present invention, such a crate is 50 constituted by a body portion generally indicated at 10, a bottom 11, and a cover or top 12. The body portion 10 comprises four relatively vertical side sections 13, 14, 15 and 16, spaced from each other, with each section permanently and flexibly joined to adjacent sections by upper and

lower and, if desired, intermediate encircling wires, bands or equivalent binding elements such as indicated at 17, 18. The ends of each wire 17, 18 are permanently connected together or, equivalently, are stapled or otherwise secured to a common section. The binding wires 17, 18 are secured to the several sections as by stapling, as indicated at 20, whereby to extend tautly throughout the width of each section. The portions 21 of the wires 17 and 18 which extend 10 between the several sections are of sufficient length as to permit each section to be folded over in overlying parallel relation on an adjacent section and may be slightly in excess thereof. By reference to Fig. 2, it will be seen that such slack wire 15 portions 21 constitute hinges between the sections which permit the enclosing structure formed by the connected sections to be collapsed as shown in Fig. 2. It will further appear that the collapsed structure as shown in Fig. 2 requires only 20 the single manipulation of opening out and bringing opposed sections into substantial parallelism as the first step in assembly of the set-up crate.

The several sections 13, 14, 15 and 16 may each 25 be constituted by a single or a plurality of parallel thin strips of veneer or like material battened or cleated together adjacent their bottom edges by lower interior cleats 24, the wire securing staples 20 also serving to secure the strips to said cleats 24. By reference to Fig. 1, the lower 30 cleats are in length the substantial width of the box sections and are thus so proportioned that the ends of the cleats of adjacent sections are spaced and are out of contact when the crate is finally assembled. That is to say, there is a gap 35 between the adjacent edges of the respective sections, with the binding wire or band 18 forming the only connection between the sections.

Upon opening out of the enclosing structure 40 formed by the flexibly connected sections, in such manner that opposed sections are brought into substantial parallelism, the bottom 11 may be inserted and pressed downwardly until it engages and rests on the aforesaid bottom cleats 24. The bottom 11 may be fabricated from a plurality of 45 relatively thin strips of material held together by suitable longitudinally extending strips, and its dimensions are such as to snugly engage the inner faces of the side sections and to tension the portions 21 of the lower wire 18 which extend 50 between the several sections. The proper placement of the bottom 11 as described thus acts to locate the side sections 13, 14, 15 and 16 with respect to each other, and at the same time gives 55 to the resulting structure a high degree of rigid-

ity and reinforcement so as to overcome any tendency of the crate to collapse.

Interior cleats 25 are also arranged to extend transversely along the top edges of the opposed sections 14, 16, with interior cleats 26 similarly arranged on opposed or end sections 13, 15. Like the lower cleats, the cleats 25, 26 are secured by staples 20 and extend substantially the width of the sections so that adjacent ends of the cleats do not abut, either when the body portion is collapsed or when it is set up for assembly.

According to the present invention, I propose to utilize a flush type of cover or top as indicated at 12, Fig. 1. Such a cover or top is designed to lie flush on the top of the crate structure and, accordingly, has no function of defining the top portions of the several side sections with respect to each other, or of imparting to the upper portion of the enclosing structure any property of rigidity or reinforcement. In order to provide such properties independently of the cover or top, I provide reinforcing bars 27, 28, preferably one for each of the ends of the crate. Such bars are dimensioned as to extend between the interior top cleats 25 and to fit snugly therebetween whereby to tension the slack portions 21 of the upper encircling wire 17 and thus to locate the mouth or upper portions of the several side sections with respect to each other. Preferably, the reinforcing bars 27, 28 are permanently yet pivotally carried by the opposed end sections 13, 15 of the crate body portion, and such may be conveniently accomplished by nailing each of the bars 27, 28 to the top interior cleat 26 thereof with a single nail 29, whereby such bars may be turned about the axis of the latter. For added rigidity and reinforcement, the ends of the cleats 25 are undercut as at 30, such under cut portions forming a seat for the ends of the reinforcing bars 27, 28 as they are swung into position.

By reference to Figs. 3, 4, 5 and 6, wherein is illustrated the various steps of assembly, it will be seen that the collapsed enclosing structure constituted by the flexibly secured side sections as indicated in Fig. 2 is first opened out so that the opposed sections are in substantial parallelism. The reinforcing bars may assume the position indicated in Fig. 3. Thereupon the bottom 11 is inserted through the upper mouth of the resulting structure and pressed downwardly to abut against the upper surfaces of the bottom cleats 24. Thereupon the reinforcing bars 27 and 28 may be manually turned about axis of nail 29 and forced into the seats formed by undercut portions 30 of opposed upper cleats 25, as indicated in Fig. 5. By reason of the snug fit of the bottom 11 and the dimensioning of the reinforcing bars 27, 28, the resulting structure is of a rigid nature and is suitably reinforced along its bottom and top edges, with the slack portions 21 of wires 17, 18, drawn tautly and diagonally between adjacent sections of the body portion. Upon setting the reinforcing bars 27, 28 into their final position, they may be suitably so held as by a nail 31 driven therethrough and extending into the top cleat 26 of the end sections.

Upon suitable packing of articles within the crate structure, the top 12 may be laid thereon and will engage flush on the top surfaces of cleats 25, 26 and reinforcing bars 27, 28. If it is desired to pack the crate above the horizontal plane of the mouth of the crate, such type of cover may bulge and thus conform itself to the upper level of the packed articles, as necessary.

The cover 12 may be secured to the crate structure by conventional means, of which the means shown are illustrative. Such securing means may comprise loops 32 secured to the top at four intermediate points thereof, preferably by having the ends of the loops held between the longitudinal and transverse strips which form the top. The said loops 32 are of sufficient length as to extend downwardly along the outer surfaces of the side sections and to be threaded underneath the top binding wire 17, as by providing a cut-out portion 33 in the side sections so as to permit the loops to be threaded rearwardly of the binding wire. Upon the cover being pressed downwardly into its final position, the ends of the loops may be bent upwardly with the loops thus holding the cover 12 to the binding wires 17, as indicated in Fig. 6.

In Fig. 7 I have illustrated a modification of the above described arrangement. In such modified construction the opposed end sections are provided with top cleats arranged exteriorly thereof. Reference is made to the modified end section 13a provided with a transversely extending top cleat 26a arranged exteriorly thereof, the reinforcing bar 27a being thus pivotally secured to one of the vertical strips from which said end section 13a is fabricated. The ends of the reinforcing bar 27a engage in recesses or seats 30a formed in the upper cleats 25a of the front and rear side sections, such cleats 25a being arranged interiorly of the sections as indicated in the Fig. 1 construction. According to the modified form the exterior top cleats 26a may be undercut as at 33a to receive the cover loops 32a as indicated.

It will be obvious that without material modification all of the upper cleats can be disposed exteriorly with the reinforcing bars disposed relatively interiorly of the end sections 13, 15 and engaging against the ends which project beyond the vertical strips of cleats analogous to cleats 25 but disposed exteriorly rather than interiorly of the structure.

Other provisions for the carrying and the insertion of the reinforcing bars may be utilized within the scope of the present invention. One such modification is illustrated in Fig. 8 in which reinforcing bars are carried by the cover or top 12b. According to this modification, the reinforcing bar 27b is nailed or otherwise secured on the under surface of the cover or top 12b, and upon the crate being suitably packed with the articles to be shipped, the cover may be applied thereto and simultaneously the bar 27b, and also its companion bar at the other end of the cover, inserted between the longitudinal upper cleats 25, as in Fig. 1, to perform the same function of properly spacing and locating the opposed sides of the crate and giving rigidity and reinforcement thereto.

It will be further evident that the reinforcing bars need not be physically carried by either the body portion of the crate or the cover but may be supplied separately therefrom. According to such further modification, the side sections minus the reinforcing bars as indicated in Fig. 3 may be set up and its bottom inserted and set as indicated in Fig. 4. Thereupon reinforcing bars may be forced downwardly into the seats 30 provided in cleats 25 and, if desired, thereupon nailed or otherwise secured in place.

While in the foregoing description, the bottom cleats have been illustrated and described as interiorly arranged, such may, like the top cleats, be arranged exteriorly as when "face-packing" is

desired. For example, the cover 12 may be applied to the enclosing structure provided with exterior cleats, and the crate inverted, and thereupon carefully packed against the under-surface of the cover through the open bottom end. Thereupon a slip type of bottom is inserted into the open mouth formed by the normally bottom end of the crate structure, and permanently secured thereto. In opening such a face-packed 10 crate, the cover or top 12 is removed as is usual to display the now uppermost and carefully packed layer of its contents.

The advantages of the above-described crate will be evident. The crate parts are capable of 15 manufacture by machine methods and require, during fabrication, a minimum amount of labor in the cutting and dimensioning thereof. The permanently joined sections further require the minimum amount of manipulation to set them 20 up and no expensive machinery to secure binding wire ends or the like. The arrangement is further such as to be fool-proof, that is to say, the enclosing structure formed by the side sections is opened up in one operation, the bottom is thereupon inserted and automatically sets the bottom 25 portion of the crate to shape and size. The proper adjustment of the reinforcing bars is next effected in a simple and expeditious manner to set the upper portion of the crate to shape and size. 30 When the crate has been filled, the cover is applied and secured by simple fastening means. In the modified form of applying the reinforcing bars as indicated in Fig. 8, the application of the cover and the fitting of the reinforcing bars is in effect a single operation. The resulting structure, although light in weight and fabricated from thin, light-weight materials, possesses an 35 unusual degree of strength, rigidity, and durability. If desired, the crate when emptied may be 40 collapsed and then stored or returned to the shipper. In any event, the collapsed crate utilizes a minimum amount of space.

Without further analysis, the foregoing will so fully reveal the gist of this invention that others 45 can by applying current knowledge readily adapt it for various applications without omitting certain features that from the standpoint of the prior art fairly constitute essential characteristics of the generic or specific aspects of this invention, and therefore such adaptations should and are intended to be comprehended within the meaning and range of equivalency of the following claims.

I claim:

55 1. A rectangular shipping crate comprising pairs of side sections, means for flexibly and permanently securing each of said side sections to adjacent sections and in spaced relation thereto, whereby said sections form a collapsible structure, a bottom unit for insertion in said structure and operative to locate the relatively lower portions of the sections with respect to each other, and reinforcing bars operative between a pair of side sections for locating the relatively upper portions of said side sections with respect to each other.

60 2. A rectangular shipping crate comprising pairs of side sections, means for flexibly and permanently securing each of said side sections to adjacent sections and in spaced relation thereto, whereby said sections form a collapsible enclosing 65 structure, a bottom unit for insertion in said structure and operative to locate the relatively lower portions of the sections with respect to each other, reinforcing bars for locating the relatively 70 other, reinforcing bars for locating the relatively 75

upper portions of the sections with respect to each other, and a flush top cover for said structure.

3. A rectangular shipping crate comprising pairs of side sections, means for flexibly and permanently securing each of said side sections to adjacent sections and in spaced relation thereto, whereby said sections form a collapsible enclosing structure, a bottom unit for insertion in said structure and operative to locate the relatively lower portions of the sections with respect to each other, reinforcing bars each carried by a side section of a pair and operative between the side sections of another pair for locating the relatively upper portions of said side sections with respect to each other.

4. A rectangular shipping crate including pairs of side sections, means for flexibly and permanently securing each of said side sections to an adjacent section and in spaced relation thereto whereby said sections form a collapsible structure, a bottom unit for insertion in said structure and operative to locate the relatively lower portions of said side sections with respect to each other, a flush type cover, and reinforcing bars carried by said cover and operative between a pair of side sections for locating the relatively upper portions of the side sections with respect to each other.

5. A rectangular shipping create comprising pairs of side sections including transversely extending cleats along the top thereof, means for flexibly and permanently securing each of said sections to an adjacent section and in spaced relation thereto, whereby said sections form a collapsible enclosing structure, a bottom unit for insertion in said structure and operative to locate the relatively lower portions of said sections with respect to each other, and reinforcing bars operative between the cleats of side sections of a pair for locating the relatively upper portions of said side sections with respect to each other.

6. A rectangular shipping crate comprising pairs of side sections including transversely extending cleats along the top thereof, means for flexibly and permanently securing each of said sections to an adjacent section and in spaced relation thereto, whereby said sections form a collapsible enclosing structure, a bottom unit for insertion in said structure and operative to locate the relatively lower portions of said sections with respect to each other, and reinforcing bars each pivotally carried by the cleats of a pair of sections and operative between the cleats of another pair of sections for locating the relatively upper portions of said side sections with respect to each other.

7. A rectangular shipping crate comprising pairs of side sections, flexible encircling binding means secured to the top and bottom portions of each section and operative to secure adjacent sections together permanently and in spaced relation whereby said sections form an enclosing structure, said binding means extending between sections, and the length of said means between sections being of the order as to permit adjacent sections to fold on one another in parallel relation, a bottom adapted for insertion in said structure and operative to tension the portions of the lower binding means extending between sections and to locate the bottom portions of said side sections with respect to each other, and reinforcing bars operative between a pair of side sections to tension the portions of the top binding means extending between the sections and

to locate the top portions of the side sections with respect to each other.

8. A rectangular shipping crate comprising pairs of side sections, flexible encircling binding means secured to the top and bottom portions of each section and operative to secure adjacent sections together permanently and in spaced relation whereby said sections form an enclosing structure, said binding means extending between sections, and the length of said means between sections being of the order as to permit adjacent sections to fold on one another in parallel relation, a bottom adapted for insertion in said structure and operative to tension the portions of the lower binding means extending between sections and to locate the bottom portions of said side sections with respect to each other, and reinforcing bars each carried by a side section of a pair and operative between side sections of another pair to tension the portions of the top binding means extending between sections and to locate the top portions of the sections with respect to each other.

9. A rectangular shipping crate comprising pairs of side sections, flexible encircling binding means secured to the top and bottom portions of each section and operative to secure adjacent sections together permanently and in spaced relation whereby said sections form an enclosing structure, said binding means extending between sections, and the length of said means between sections being of the order as to permit adjacent sections to fold on one another in parallel relation, a bottom adapted for insertion in said structure and operative to tension the portions of the lower binding means extending between sections and to locate the bottom portions of said side sections with respect to each other, and reinforcing bars each pivoted to a section of a pair and operative between the sections of another pair to tension the portions of the top binding means extending between sections and to locate the upper portions of the sections with respect to each other.

MASON FOSHEE.
